CIRCUIT FOR TRANSMITTING HIGH-FREQUENCY ELECTRIC OSCILLATIONS

Maximiliaan Julius Otto Strutt and Aldert van der Ziel, Eindhoven, Netherlands, assignors to Hartford National Bank and Trust Company, Hartford, Conn., as trustee

Application November 15, 1946, Serial No. 737,572
In the Netherlands January 13, 1941

Section 1, Public Law 690, August 8, 1946
Patent expires January 13, 1961

7 Claims. (Cl. 250—36)

1

This invention relates to a circuit for generating high-frequency electric oscillations with the aid of a discharge tube which comprises an input electrode of adjustable biasing potential and whose input circuit includes an oscillatory circuit tuned to the frequency of the oscillations to be generated.

It is known that a circuit of this kind functions with difficulty if the frequency of the oscillations to be generated is so high that one has to reckon with the transit time of the electrons in the tube. If the transit time is appreciable compared with the period of the oscillations, then the input capacity of the discharge tube varies with the biasing potential of the input electrode. Hence, in the case of a variation of the biasing potential the tuning of the input circuit is also varied. Moreover, at those high frequencies a virtual ohmic resistance occurs between the input electrode and the cathode, the reciprocal value of said resistance being usually referred to as electronic damping and being also, variable with the biasing potential of the input electrode. Consequently, the damping of the input circuit is also varied with a variation of the biasing potential.

It is known to eliminate the above-stated undesirable variations of the input capacity of the tube by including an ohmic resistance which is not short-circuited for high-frequency, in that part of the cathode lead which is common to the input and the output circuits. The alternating current of the cathode brings about a voltage across the said resistance, which is at least substantially in phase with the input alternating voltage impressed upon the input electrode and whose value is variable with the slope of the tube characteristic and hence with the biasing potential of the input electrode. The voltage produced across the resistance causes in turn a current from the cathode to the input electrode through the natural capacity between these two electrodes, which current is also variable with the biasing potential of the input electrode and leads by about 90° relatively to the input alternating voltage. This current may be considered as a result of a negative capacity which apparently exists between the input electrode and the cathode and whose value is variable with the biasing potential of the input electrode, said capacity, if it has the correct value, neutralizing the undesirable variations of the input capacity.

The above-stated undesirable damping variations may also be eliminated, as is well known, by providing an ohmic resistance which is not short-

2

circuited for high frequency, in that part of the cathode lead which is common to the input and the output circuits. For this purpose the ohmic resistance must generally have a higher value than that necessary for compensating the capacity variations. The elimination of the damping variations is, however, facilitated by connecting a capacity in parallel with the ohmic resistance, the impedance of this capacity for the frequencies to be transmitted being at least of the order of magnitude of the ohmic resistance. When a suitable parallel capacity is used, it is even possible to eliminate simultaneously the undesirable capacity variations and the damping variations.

When oscillations of high and very high frequencies are to be generated, a practice heretofore adopted has been to use a so-called suction-grid tube; that is, a discharge tube comprising at least one auxiliary electrode serving as a suction grid or space-charge grid disposed between the input electrode and the cathode, and being positively biased with respect to the cathode. It has now been found that in a suction-grid tube, the above-described method of eliminating variations of the input capacity and of the input damping with a variation of the biasing potential of the input electrode does not lead to the desired result, for the reason that these variations are of opposing sense relative to the variations which occur in a tube having no suction grid. When the suction grid is omitted the input capacity and the input damping increase according as the biasing potential of the input electrode becomes less negative. But in a suction-grid tube a decrease of the input capacity and of the input damping takes place in the region of biasing potentials in which the tube is generally used.

According to the invention, in a circuit comprising a suction-grid tube an elimination or decrease of the variations of the input capacity and the input damping in the case of a variation of the biasing potential of the input electrode is obtained by introducing an ohmic resistance into the path of high frequency currents between the resonant portion of the output circuit and the cathode, by shunting said ohmic resistance by a capacity which offers a relatively high impedance to said currents, and by adopting other measures, the details of which will presently be explained.

Such connection of the ohmic resistance has the effect that a compensating current flows to the input electrode, whose phase is opposite to

that of the compensating current which, in the known circuit comprising a tube without suction grid, flows to the input electrode.

The invention will be explained more fully by reference to the accompanying drawings, in which, Figs. 1, 2, and 3 show by way of example certain typical embodiments the differentiating features of which will also be explained.

Fig. 1 shows a discharge tube 1 containing a cathode 2, a suction grid 3, an input electrode (control grid) 4 and an output electrode (anode) 5. A resonant input circuit 6 tuned to the frequency of the oscillations to be generated is, on the one hand, connected to the control grid 4 and, on the other hand, coupled via a separating condenser 7 to the cathode 2. Across a resistance 8 the control grid has supplied to it a variable biasing potential which may be generated for example in known manner by a regulating rectifier for automatic volume control.

The suction grid 3 is coupled for high frequency currents via a separating condenser 9 to the cathode, while across a resistance 10 a positive biasing potential is supplied to the suction grid.

The resonant output circuit 11 is on the one hand connected to the anode 5 and on the other hand coupled via a separating condenser 12 to the cathode 2, while the direct voltage of the anode is supplied via a resistance 13.

In order that variations of the input capacity and/or of the input damping with a variation of the control-grid biasing potential may at least partly be eliminated, the alternating current path of the output circuit includes a resistor 14 which is connected to the cathode 2. This connection is coupled for high frequency currents across condenser 9 to the suction grid 3 and across condenser 7 to that extremity of the resonant input circuit 6 which is remote from the control grid. The other extremity of resistor 14 is coupled via a condenser 15 to the input electrode 4. The resistor 14 as shown in Fig. 1 is devoid of any shunting capacitor such as would be conventionally used, and, accordingly, there is no effective short circuit for high frequency currents between the suction grid 3 and the resonant circuit 11.

The operation of the circuit may be explained as follows:

The suction grid 3 has a constant potential. A substantially constant direct current passes out of the cathode and flows partly to the suction grid 3 and for the remaining part to the anode 5. The current distribution between the suction grid and the anode is controlled by the voltage active on the control grid 4. When the control grid becomes more positive a greater part of the cathode current flows to the anode 5 and when the control grid becomes more negative a greater part of the cathode current flows to the suction grid 4. Consequently, if an alternating voltage is active on the control grid 4, an alternating current flows from the suction grid through the output circuit to the anode. For alternating currents of the frequency to be transmitted the suction grid consequently performs the function which in tubes without suction grid is fulfilled by the cathode.

The alternating current flowing from the suction grid to the cathode brings about a voltage drop across the resistance 14, which is in phase with the alternating voltage of the control grid and whose value is variable with the mutual conductance of the tube, and hence with the biasing potential of the control grid. This voltage drop

produces in turn a current via the condenser 15 to the control grid, which current lags by about 90° relatively to the alternating voltage of the control grid. This current may be regarded as a result of a capacity which apparently exists between the control grid and the suction grid and whose value is variable with the biasing potential of the control grid. Said capacity, if it has the correct value, compensates at least partly for undesirable variations of the input capacity. The compensating current flowing to the input electrode contains also a component which is in anti-phase with the alternating voltage of the control grid and which, if it has the correct value, may at least partly eliminate the variations of the input damping. To attain this object it is advantageous to connect a condenser in parallel with the resistance 14, of which condenser the impedance for the oscillations to be generated is at least of the order of magnitude of the resistance 14.

In Fig. 2 this parallel condenser is indicated by 16. The circuit of Fig. 2 differs moreover from that of Fig. 1 in that the tube, in addition to the electrodes already mentioned, contains a screen grid 17 which is located between the control grid and the anode and which has a positive biasing potential supplied to it via a resistance 18. The function of the condenser 15 in the circuit of Fig. 1 is fulfilled in the circuit of Fig. 2 by the natural screen grid-control grid capacity, for which purpose the screen grid is connected for high-frequency currents via a separating condenser 19 to that extremity of the resistance 14 which is remote from the suction grid.

Suction-grid tubes frequently involve the drawback that the natural inductance of that part of the supply conductor for the suction grid which is common to the input and the output circuits causes an undesirable coupling between the input and the output circuits, which coupling results in damping of the input circuit. It has previously been suggested to eliminate this drawback by providing the suction grid with two separate supply conductors and connecting the suction grid for high-frequency currents via one of these supply conductors to the input circuit and via the other to the output circuit.

Fig. 3 shows how the invention can be used in a tube whose suction grid is provided with two supply conductors. In the circuit of Fig. 3 the suction grid lead 20 is coupled across capacitor 9 to the cathode and thence across capacitor 1 to that extremity of the input circuit 6 which is remote from the control grid. The conductor 21 connects the suction grid 3 to a resistor 10 for supply thereto of a positive direct current potential. Conductor 21 also connects the suction grid through an alternating current path to the resonant output circuit 11. This path includes resistor 14 shunted by capacitor 16 and also the blocking capacitor 12. The value of capacitor 16 is so chosen as to offer a high impedance to the high frequency currents generated. For the rest, the circuit fully corresponds to that of Fig. 2.

In the circuits of Figs. 2 and 3 it is possible to give the resistance 14 and the parallel condenser 16 such values that the input capacity as well as the input damping are at least substantially invariable with the biasing potential of the control grid. The value of the resistance 14 required therefor is generally comprised between 50 and 75 500 ohms, while the condenser 16 may be, for

example, of the order of magnitude of 10 micro-microfarads.

Theoretically the cathode 2 which carries only direct current could alternatively be connected to the extremity of the resistance 14 which is remote from the suction grid. The circuit shown in the drawing, in which the cathode is coupled for high-frequency currents directly to the suction grid is, however, preferable since in this case the occurrence of an alternating voltage between the suction grid and the cathode, which alternating voltage would exert a controlling action on the cathode current, is avoided.

I claim:

1. A high frequency oscillator circuit arrangement comprising an electron discharge tube having arranged in succession a cathode, a space charge electrode otherwise termed a suction grid, a control grid and an anode, an oscillatory circuit tuned to the frequency of the oscillations to be generated and coupled between said control grid and cathode, an output circuit coupled between said anode and cathode and comprising a parallel tuned resonant circuit having one terminal thereof coupled to the anode and ohmic resistor means coupled in series with said resonant circuit and having the free end thereof coupled for radio frequencies to said base charge electrode, and means to apply to said control grid potential variations occurring at the interconnection between said resonant circuit and said resistor means whereby a feedback potential having an oscillation-sustaining phase relationship with respect to the voltage of said oscillatory circuit is applied to said control grid.

2. A high frequency oscillator circuit arrangement comprising an electron discharge tube having arranged in succession a cathode, a space charge electrode otherwise termed a suction grid, a control grid and an anode, an oscillatory circuit tuned to the frequency of the oscillations to be generated and coupled between said control grid and cathode, an output circuit coupled between said anode and cathode and comprising a parallel tuned resonant circuit having one terminal thereof coupled to the anode and ohmic resistor means coupled in series with said resonant circuit and having the free end thereof coupled for radio frequencies to said space charge electrode, and means to capacitatively couple said control grid to the interconnection between said resonant circuit and said resistor means whereby a feedback potential having an oscillation-sustaining phase relationship with respect to the voltage of said oscillatory circuit is applied to said control grid.

3. A high frequency oscillator circuit arrangement comprising an electron discharge tube having arranged in succession a cathode, a space charge electrode otherwise termed a suction grid, a control grid and an anode, an oscillatory circuit tuned to the frequency of the oscillations to be generated and coupled between said control grid and cathode, an output circuit coupled between said anode and cathode and comprising a parallel tuned resonant circuit having one terminal thereof coupled to the anode and ohmic resistor means coupled in series with said resonant circuit and having the free end thereof coupled for radio frequencies to said space charge electrode, a capacitor connector in parallel with said resistor means and having an impedance at the frequency of the oscillations to be generated of the order of magnitude of that of said resistor, and means to capacitatively couple said control grid to

the interconnection between said resonant circuit and said resistor means whereby a feedback potential having an oscillation-sustaining phase relationship with respect to the voltage of said oscillatory circuit is applied to said control grid.

4. A high frequency oscillator circuit arrangement comprising an electron discharge tube having arranged in succession a cathode, a space charge electrode otherwise termed a suction grid, a control grid and an anode, an oscillatory circuit tuned to the frequency of the oscillations to be generated and coupled between said control grid and cathode, an output circuit coupled between said anode and cathode and comprising a parallel tuned resonant circuit having one terminal thereof coupled to the anode and ohmic resistor means coupled in series with said resonant circuit and having the free end thereof coupled for radio frequencies to said space charge electrode, and means comprising a capacitor to couple said control grid to the interconnection between said resonant circuit and said resistor means whereby a feedback potential having an oscillation-sustaining phase relationship with respect to the voltage of said oscillatory circuit is applied to said control grid.

5. A high frequency oscillator circuit arrangement comprising an electron discharge tube having arranged in succession a cathode, a space charge electrode otherwise termed a suction grid, a control grid and an anode, an oscillatory circuit tuned to the frequency of the oscillations to be generated and coupled between said control grid and cathode, an output circuit coupled between said anode and cathode and comprising a parallel tuned resonant circuit having one terminal thereof coupled to the anode and ohmic resistor means coupled in series with said resonant circuit and having the free end thereof coupled for radio frequencies to said space charge electrode, and means comprising a screening grid electrode interposed between said control grid and said anode and in capacitive relationship with said control grid to capacitively couple said control grid to the interconnection between said resonant circuit and said resistor means whereby a feedback potential having an oscillation-sustaining phase relationship with respect to the voltage of said oscillatory circuit is applied to said control grid.

6. A high frequency oscillator circuit arrangement comprising an electron discharge tube having arranged in succession a cathode, a space charge electrode otherwise termed a suction grid, a control grid and an anode, an oscillatory circuit tuned to the frequency of the oscillations to be generated and coupled between said control grid and cathode, an output circuit coupled between said anode and cathode and comprising a parallel tuned resonant circuit having one terminal thereof coupled to the anode and ohmic resistor means coupled in series with said resonant circuit and having the free end thereof connected to said cathode and capacitively coupled for radio frequencies to said space charge electrode, a capacitor connected in parallel with said resistor means and having an impedance value at the frequency to be generated of the order of magnitude of that of said resistor means, and means comprising a screening grid electrode interposed between said control grid and said anode and in capacitive relationship with said control grid to apply to said control grid potential variations occurring at the interconnection between said resonant circuit and said resistor means whereby a feedback

potential having an oscillation-sustaining phase relationship with respect to the voltage of said oscillatory circuit is applied to said control grid.

7. A high frequency oscillator circuit arrangement comprising an electron discharge tube having arranged in succession a cathode, a space charge electrode otherwise termed a suction grid, a control grid and an anode, an oscillatory circuit tuned to the frequency of the oscillations to be generated and coupled between said control grid and cathode, an output circuit coupled between said anode and cathode and comprising a parallel tuned resonant circuit having one terminal thereof coupled to the anode and ohmic resistor means coupled in series with said resonant circuit and having the free end thereof capacitively coupled for radio frequencies to said cathode and connected to said space charge electrode, a capacitor connected in parallel with said resistor means and having an impedance value at the frequency to be generated of the order of magnitude of that of said resistor means, and means comprising a screening grid electrode interposed between said

5 control grid and said anode and in capacitive relationship with said control grid to apply to said control grid potential variations occurring at the interconnection between said resonant circuit and said resistor means whereby a feedback potential

10 having an oscillation-sustaining phase relationship with respect to the voltage of said oscillatory circuit is applied to said control grid.
